UNITED STATES PATENT OFFICE.

JOSEPH C. CRAMER, OF LEADVILLE, COLORADO.

PICK.

SPECIFICATION forming part of Letters Patent No. 249,311, dated November 8, 1881.

Application filed July 22, 1881. (Model.)

To all whom it may concern:

Be it known that I, JOSEPH C. CRAMER, of Leadville, in the county of Lake and State of Colorado, have invented certain new and useful Improvements in Picks, of which the following is a specification.

My invention relates to mining-picks; and it consists in the particular means by which the wedge is prevented from jarring out, and in a peculiar construction of handle-socket, all as hereinafter described, and pointed out in the claim.

In the accompanying drawings, Figure 1 is a plan view of the pick and handle, the socket being shown in section. Fig. 2 is a cross-section taken on line $x-x$ of Fig. 1. Fig. 3 is a side elevation of the socket with the handle and pick removed, and Fig. 4 is a perspective view of the wrench.

Similar letters of reference indicate corresponding parts.

In the drawings, A represents the pick, B the handle, and C the socket-head.

The pick may be of any desired length and curvature, and may have any form of points. In the center of its length, on the under side, is formed the concave, conical, or double-inclined seat a, which fits over the correspondingly-shaped, or rather roof-shaped, rest c, formed in the horizontal pick-socket or eye d, formed through the socket-head. When the pick is in place in the socket-head it is secured there preferably by the wedge F. In the end of the socket-head is placed the set-screw h, which may be turned into the eye or pick-socket the proper distance before the wedge is driven in, or it may be tightened upon the wedge afterward, as desired. This screw is of great advantage in removing the wedge for removing the pick from the socket-head.

The socket-head C should be made of mallea-

ble iron or cast-steel, and the handle-eye e should be enlarged at the inner end, as shown at e' in Fig. 2.

In securing the handle and socket-head together the wedge b should first be inserted a short distance into the end of the handle, and then the handle and wedge placed in the handle-socket and the handle driven home upon the wedge b, which will cause the end of the handle to be spread into the enlarged portion e' of the handle-socket, and thus securely hold the handle and socket-head together.

The pocket-wrench I is provided for operating the set-screw h; or the screw may be operated by means of an ordinary screw-driver, if desired.

The many advantages of this construction of pick are obvious, and need not therefore be enumerated.

I am aware that it is not new to provide a pick with a recess to receive a projection on the socket, or to hold the pick in the socket by a follower swiveled to the end of a thumb-screw, or by a key driven through the socket, or by a spring-key; but

What I claim as new and of my invention is—

The combination, with the wedge F and screw h, of the socket-head C, having in the eye d a roof-shaped rest, c, to fit a corresponding recess in the pick, and in the front a hole for the reception of the threaded shank of screw, and an enlarged cavity to receive the screw-head, as shown and described, whereby the screw works in threads of the socket-piece, and its head is sunk below the front surface to prevent the wedge from jarring out.

JOSEPH CYRUS CRAMER.
